UNITED STATES PATENT OFFICE

2,213,287

AIR SUPPLY FITTING

Charles Frederick Priest, Middlesbrough, England

Application March 25, 1939, Serial No. 264,271
In Great Britain April 1, 1938

3 Claims. (Cl. 110—182.5)

This invention relates to burners and air supply fittings for kilns, furnaces, and the like, particularly to burners and air supply fittings of the type which are projected through the wall of the kiln, furnace, and the like and held in position by some fastening means associated with the outside of the kiln, furnace, and the like.

The object of the invention is to provide improvements in the means for securing burners and air supply fittings of the type described.

According to the present invention a plurality of pairs of lugs project outwardly from the external face of the kiln, furnace, or the like or of a member attached thereto, and bars are disposed between said pairs of lugs and retained therein by wedges, the bars also engaging the burner or air supply fitting when said burner or air supply fitting is disposed in the aperture through the wall of the kiln, furnace, or the like.

One form of apparatus constructed in accordance with this invention, adapted for the purpose of securing a burner in the wall of a kiln, furnace, or the like, is illustrated in the accompanying drawing, wherein:

Fig. 1 is an end elevation.

Fig. 2 is a fragmentary longitudinal sectional elevation, taken on line II—II of Fig. 1; and

Fig. 3 is a fragmentary plan view.

In the drawing, an aperture 1 through the wall 2 of the kiln, furnace or the like, hereinafter referred to as the kiln, through which the burner 3 is projected, is surrounded at its outer end by an annular ring 4 which is rigidly secured to the outer face 5 of the kiln wall 2 by bolts or the like passed through holes 6. The ring 4 may be provided with an inwardly tapering annular flange 7, adapted to project into the aperture 1 in the kiln wall, the internal periphery 8 of the annular flange forming a tapered seat for the correspondingly shaped outer end 9 of the burner 3 so that when said burner 3 is passed through the aperture 1 it will seat itself in said seat 8 and make a gas-tight fit therein.

The outer face of the annular ring 4 is provided with four pairs of lugs 10 which project outwardly therefrom, the lugs being cast or otherwise rigidly secured to the ring 4. The lugs 10 are all parallel and are preferably vertical in end elevation, the lugs forming a pair being disposed side by side so as to form a vertical gap 11 therebetween. Each pair of lugs is preferably disposed at a corner of an imaginary rectangle having vertical and horizontal sides, 12 and 13, so that the gaps 11 in the two top pairs are dis-

posed vertically above the gaps in the two bottom pairs, the two vertical sides 12 of the rectangle being disposed outside the walls 14 of a tubular member forming the fuel passage 15 through the burner 3, and the centre of the rectangle being preferably coincident with the axis of the burner 3 and of the annular ring 4. Each lug 10 is provided with a transverse hole 16 for the reception of a wedge 17, one wedge being adapted to pass, preferably horizontally, through the holes 16 in a pair of lugs.

The burner 3 is passed through the aperture 1 in the kiln wall 2 until its outer end 9 seats itself in the conical seating 8 in the annular ring 4. Bars 18 are provided and are disposed in the gaps 11 between the lugs 10, one bar 18 for two vertically opposite pairs of lugs 10 so that one end of the bar 18 is in the gap 11 between the upper pair of lugs and the other end is in the gap 11 between the bottom pair of lugs, and the medial portion 19 of the bar 18 engages the face of the outer end 20 of the burner 3. The wedges 17 are then passed through the holes 16 in the lugs 10 so that they engage the outer vertical faces of the holes 16 and the outer faces or edges of the ends of the bars 18. When the wedges 17 are driven tight into contact with the hole faces and the bars, the bars 18 are forced towards the outer face of the annular ring 4 and in turn force the conical end 9 of the burner 3 tight into the conical seating 8 in the annular ring 4. The burner 3 is thereby held securely in position in the kiln wall 2, and may be easily removed for replacement by knocking out the wedges 17 and removing the bars 18.

The bars 18 may be provided at their upper ends with T-heads 21 adapted to rest on the upper edges 22 of the top pairs of lugs 10 so that the bars 18 may be suspended from said lugs 10 while the wedges 17 are being driven into position.

The medial portion of the outer edges of the bars 18 may be cambered longitudinally as at 23 for strengthening purposes, whilst the inner edges of the bars may be suitably shaped so as 45 to closely engage the face of the outer end 20 of the burner 3.

It will be obvious that the invention may be used for securing any suitable type of burner or supply fitting which is projected transversely through the kiln wall, for example, air supply nozzles, tuyères, or the like.

What I claim and desire to secure by Letters Patent is:

1. In a furnace having an opening in its side 55

- wall, a seating member disposed in said opening and secured to the wall of the furnace, a tubular member supported in said seating member with one end outside of the furnace, means for removably securing said tubular member in said seating member and comprising a plurality of lugs projecting from said seating member and disposed in vertically aligned pairs, the lugs of each pair being spaced apart and provided with 10 aligned transverse openings, a pair of bars each having its ends disposed in the spaces between the lugs of two vertically aligned pairs of lugs, the intermediate portions of said bars engaging the end of said tubular member at opposite sides of 15 its opening, and a wedge disposed in the aligned openings of each pair of lugs and extending transversely of the ends of the bars thereby pressing them on the tubular member.
2. In a furnace having an opening in its side wall, a seating member disposed in said opening and secured to the wall of the furnace, a tubular member supported in said seating member with one end outside of the furnace, means for removably securing said tubular member in said 20 seating member and comprising a plurality of lugs projecting from said seating member and disposed in vertically aligned pairs, the lugs of each pair being spaced apart and provided with aligned transverse openings, a pair of bars each having its ends disposed in the spaces between the lugs of two vertically aligned pairs of lugs, the intermediate portions of said bars engaging the end of said tubular member at opposite sides of its opening, and a 25 wedge disposed in the aligned openings of each pair of lugs and extending transversely of the ends of the bars thereby pressing them on the tubular member, each of said bars having a head at its upper end for supporting the bar on its upper pair of lugs while the wedges are being set in position or removed from the lugs.

its opening, and a wedge disposed in the aligned openings of each pair of lugs and extending transversely of the ends of the bars thereby pressing them on the tubular member, each of said bars having a head at its upper end for supporting the bar on its upper pair of lugs while the wedges are being set in position or removed from the lugs.

3. In a furnace having an opening in its side wall, an annular ring secured to the furnace wall and having an annular flange projecting into said opening, the internal surface of said flange forming a tapered seat, a tubular member disposed in said opening and having on its outer surface a tapered portion forming a fluid-tight joint with the tapered seat of said flange, a plurality of lugs projecting from the outer face of said annular ring and disposed in vertically aligned pairs, the lugs of each pair being spaced apart and provided with aligned transverse openings, a pair of bars each having its ends disposed in the spaces between the lugs of two vertically aligned pairs of lugs, the intermediate portions of said bars engaging the end of said tubular member at opposite sides of its opening, and a wedge disposed in the aligned openings of each pair of lugs and extending transversely of the ends of the bars thereby pressing them on the tubular member, each of said bars having a head at its upper end for supporting the bar on its upper pair of lugs while the wedges are being set in position or removed from the lugs.

CHARLES FREDERICK PRIEST.
